United States Patent Office

Des. 188,941
Patented Oct. 4, 1960

188,941

MOBILE PESTICIDAL SPRAYER OR SIMILAR ARTICLE

Robert C. Hudson, Glencoe, Ill., and August H. Pinke
and Kenneth H. Meeker, Hastings, Minn., assignors to
H. D. Hudson Manufacturing Company, Chicago, Ill.,
a corporation of Minnesota

Filed Mar. 6, 1959, Ser. No. 54,873

Term of patent 14 years

(Cl. D31—3)

Figure 1 is a perspective view of a mobile pesticidal sprayer or similar article embodying our new design;

Fig. 2 is a view in side elevation thereof; and

Fig. 3 is a top plan view thereof.

The side of the mobile pesticidal sprayer or similar article not shown is substantially the same in appearance as the side shown.

We claim:

The ornamental design for a mobile pesticidal sprayer or similar article, substantially as shown and described.
